LOCKING LATCH

Burnie J. Craig, Los Angeles, Calif.

Application September 18, 1950, Serial No. 185,412

18 Claims. (Cl. 70—264)

1

This invention relates to a locking latch. The general object of the invention is to provide an improved vehicle door latch including novel lock means for controlling operation of the latch on a door of an automotive vehicle.

Another object of the invention is to provide door latching means including novel lock means which is operable in a novel manner to unlock the latch.

Another object of the invention is to provide a novel door latch handle assembly.

Another object of the invention is to provide a novel combined key-controlled and dial actuated tumbler controlled lock assembly.

Another object of the invention is to provide a novel push button operated latch release member and latch lock.

Another object of the invention is to provide a novel combined key and keyless actuated locking member.

A further object of the invention is to provide a latch locking means wherein a handle having a push button actuated release member is employed and wherein a dial actuated tumbler unlocking member and a key operated unlocking device mounted coaxial with the dial and mounted remote from the handle control release of the latch bolt.

A further object of the invention is to provide a vehicle door latch handle assembly which carries push button means for operating a door latch to released position and wherein a plurality of means carried on the body pillar is operable to render the push button member operative to open the door.

Other objects and advantages of the invention will be apparent from the following description taken in connection with the drawings, wherein:

Fig. 1 is a fragmentary side elevation showing a pair of vehicle doors and a pillar with the present invention applied thereto;

Fig. 2 is an elevation showing the latch mechanism;

Fig. 3 is an enlarged section taken on line 3—3, Fig. 1;

Fig. 4 is a section taken on line 4—4, Fig. 3;

Fig. 5 is an isometric view showing the coincidental locking means;

Fig. 6 is a view similar to Fig. 1, showing a modification;

Fig. 7 is a view similar to Fig. 5, showing the modification, and

Fig. 8 is a sectional view taken on line 8—8, Fig. 6, showing the dial and operating parts of the modification.

2

Referring to the drawing by reference characters, the invention is shown as embodied in door latches arranged upon doors A of a multi-door vehicle which includes door pillars B.

As shown, each latch includes a base plate 10 (Fig. 2), having a flange 11 thereon, which is provided with a slot 12 through which a bolt 13 protrudes. The bolt 13 is shown as pivotally mounted on the base plate at 14 and at its outer end supports a strike engaging roller 15.

The latches in the present disclosure are of the type shown in applicant's copending application Serial No. 103,431, filed July 7, 1949, now Patent No. 2,659,230, granted November 17, 1953.

The protruding roller 15 moves in a slot 16 in a strike member 17, arranged upon the car pillar 18. As fully described in Patent No. 2,659,230, the roller moves from one end of the slot 16 towards the other end to fully engaged position, where it is held in door closed position by a catch member 20 pivotally supported at 21 upon the base 10, and which includes notched portions 22 and 23.

The bolt 13 includes a pin 24 which rests upon the notched portion 22 when the bolt is in the disengaged position. When the bolt is moved to safety latched position, the pin engages the notch 23 and when the bolt is raised to fully engaged position (see Fig. 2), the bolt engages the notched portion 25 just above the notch 23. When so engaged the bolt cannot move downwardly to disengaged position until the catch member 20 is swung about its pivot 21 and is released, as will be hereinafter described. A tongue 25' on the base plate limits movement of the catch member in one direction.

One end of a spring 26, arranged about the pivot pin 14, engages a pin 27 on the catch 20 and urges the catch 20 to bolt holding position while the other end of the spring 26 engages a pin 28 on the bolt 13 to normally urge the bolt downwardly to disengaged position.

The bolt may be released by means of an inside remote control door handle (not shown) which is connected by a rod 31 to a rock arm 33 which is mounted on the pivot 21. The lower end of the rock arm engages an actuating pin 34 mounted on a latch releasing member 35. The rock arm will thus move the pin 34 and the pin will move the catch 20, thus permitting the spring 26 to move the latch bolt to disengaged position as the door is opened.

In order to provide means exterior of the vehicle for releasing the catch members 20 and also to provide means for locking the release means against unwarranted operation, a carriage mem-

ber 36 is provided for each catch. Each carriage member is pivoted on a pivot 37 on the base 10. One end of the carriage member 36 is raised at 36' and a snap-over spring 36'' is arranged between this raised portion 36' and the base 10 to hold the carriage member in either one of its two positions. Tongues 35', struck from the base 10, limit movement of the carriage member 36.

The carriage member 36 includes a projecting end portion 38 which extends through a slot 38' in the flange 11. The end of the portion 38 supports a roller 38''.

The carriage member is similar in some respects in construction and operation to the carriage member shown in Fig. 32 of the applicant's prior Patent No. 2,204,208, granted June 11, 1940.

Guide tongues 39 on the carriage member 36 slidably support the latch release member 35 previously mentioned. When the carriage member is in the position shown in Fig. 2 and the release member 35 is moved, the pin 34 will engage the tongue 40 on the catch 20 to move the catch. A tongue 41 on the carriage member limits movement of the release member in one direction.

When the carriage member 36 is swung about its pivot 37, the pin 34 will be disposed opposite to a slot 40' in the catch 20 so that when the release member 35 moves to releasing position, the pin 34 will move into the slot 40' without moving the catch member 20. The latch just described is fully disclosed and described in the applicant's Patent No. 2,659,230, mentioned above.

The carriage member 36 includes an elongated slot 46 which is aligned with a slot 47 in the base 10, and the latch releasing member 35 is also provided with a slot 48, aligned with the slots 46 and 47. The slots 46, 47 and 48 receive one end portion of a releasing arm 49, which may be operated from the exterior of the door, as will be described.

The releasing arm 49 is carried by an outside actuator, indicated generally at 50 (see Fig. 3). As shown, the actuator is similar to the handle assembly disclosed in Fig. 24 in the applicant's Patent No. 2,450,372, granted September 28, 1948. As shown the actuator includes a body 51, having a hand grip 52 thereon. A screw 52' holds the body 51 in place.

The body 51 includes a bore 53 in which a push member 54 is arranged. The push member 54 includes a flanged portion 55, which is normally urged against a shoulder 56 by a spring 57, which also engages a flange 58 on a support 59. The flange 58 has a tight fit in an enlarged bore 53' so that it does not rotate. A guide washer 60 engages the end of the flange 58 and a split spring 61 holds the parts assembled.

The push member 54 includes holes 63, in which pins 64 on the support 59 are arranged to slide. The pins 64 permit the push member 54 to slide axially relative to the support 59 without turning. The support 59 includes depending ears 65, on which the arm 49, previously described, is pivoted as at 66.

The arm 49 includes a bell crank portion 67 which is engaged by a pin 68 on the push member 54 and the construction is such that the arm 49 is rocked by the push member when the latter moves axially. As stated, the arm 49 extends through the slots 46, 47 and 48, the slot 47 being of a size so that it is not engaged by the releasing arm 49. The slot 48 is of a size to comfortably receive the releasing arm 49 so that as the push member 54 is pushed inwardly, the arm 49 is rocked, thus moving the latch releasing mem-

ber 35 to the right in Fig. 3 and to the left in Fig. 2.

This will cause the pin 34 on the latch releasing member 35 to engage the catch member 20, causing the catch member to be rocked, thus releasing the bolt 13 so that the latter may be moved downwardly by the spring 26 as the door opens.

This last described action occurs when the locking member is in the unlocked—that is, the position shown in Fig. 2. When the carriage member 36 is moved to the locked position and the releasing arm 49 is rocked to shift the latch releasing member 40, the pin 34 will move into the slot 40' in the catch member 20 and thus there will be no releasing action by movement of the latch releasing member 40.

Full movement of the actuating member 49 by the push button will not move the pin 34 far enough to engage the rear wall of the slot 40' so that no unlocking occurs. However, when the operator 31 is moved it will move the member 33 far enough to shift the pin 34 against the rear wall of the slot 40' and thus rock the member 20 and release the latch.

From the foregoing description it will be apparent that the latch may be released by operating the push member 54 when the carriage member 36 is in one position and that a similar operation of the pushing member 54, when the carriage member 36 is in the other position, will not serve to open the door. However, the inside release rod 31 may be operated to release the catch member and to free the bolt regardless of which position (locked or unlocked) the carriage member 36 may happen to be in. The slot 48 is wide enough so that it receives the arm 49 regardless of whether the carriage member 36 is in locked or unlocked position.

For coincidentally locking all of the locks, the rollers 38' on the carriage members 36 of the adjacent door latches are adapted to move into substantially U-shaped wings 80 (see Fig. 5), mounted at the two ends of a locking bar 81 which has an operating lever 82 connected thereto. The bar 81 includes arms 83 which are pivoted as at 84 to uprights 85 struck from a base 86 of a coincidental lock assembly 86'.

The uprights 85 are supported by braces 85' bent up from the base 86. This assembly also includes a vertical portion 87 which is arranged upon the vehicle pillar with the lever 82 accessible from within the vehicle. The portion 87 supports the lock body 88 of a dial and key operated lock body. The lock 88 includes a projecting cylindrical head member 89 which has a crank 90 mounted thereon (see Fig. 3). The crank 90 includes a crank pin 91 which fits in a slot 92 in the locking bar 81.

The lock is adapted to be operated, by means of a suitable key or by correctly positioning the tumblers (to be described), from a neutral position in either direction. This turning of the lock moves the crank 90 from an upper position to a lower position, and vice versa, and in so doing the pin 91, moving in the slot 92 in the locking bar 81, raises and lowers the bars 81 and thus raises and lowers the wings 80.

The lever 82 on one side of the vehicle is connected by a Bowden wire 93 with a similar lever 82 on the other side of the vehicle, with the Bowden wire preferably passing beneath the vehicle body. The Bowden wires are so connected to the levers that when the lever on one side is depressed or raised the lever on the other side of the vehicle will be also depressed or raised.

The coincidental lock assembly may be suitably secured on the vehicle body in a position wherein the wings 80 are disposed to receive the associated roller 38" when each door is closed. A snap-over spring 95 holds the bar 81 and wings 80 in either up or down position after they have been moved to such position. Stops 96 limit movement of the bar 81.

When two adjacent doors are closed and the rollers 38" are in their respective wings 80 with the locking bar 81 in the position shown in Fig. 2, the locking members 36 will be in a position to cause the associated latches to be unlocked. When, under this condition, the lock 88 is moved to locked position, that is, the lock is moved so that the pin 91 is lowered and the locking bar 81 is moved downwardly, the wings 80 will move downwardly and thus will move the associated rollers 38" and will move the associated carriage members 36 downwardly so that the latter will be in locked position.

The slot 92 is of a shape to permit the pin 91 to move up and down therein. When the pin 91 is in a normal position and the wings are in locked position the pin will be adjacent to the lower face of the slot 92. Now when the lock is moved the pin 91 will move downwardly and since the pin engages the lower wall of the slot 92 in the bar 81 the pin will push down and will move the bar 81 down to the locked position. When the wings 80 are in the reverse position the pin will be adjacent to the upper edge of the slot, and when the pin is moved upwardly the bar 81 will be raised to unlocked position. Thus the bar 81 may be moved by the pin 91 while still allowing the wings 80 to be moved to locked and to unlocked position by the lever 82 independent of the position of the pin 91.

As the wings 80 move about the pivot 84 from locked to unlocked position, there is a slight forward and backward movement of the wings relative to the face 87. The wing support, however, is slightly flexible and loosely fitted together so that this slight movement of the wings 80 does not cause a binding action due to the rollers 38" pressing against the wings.

When any key of a lock 88 is turned from locked to unlocked position or vice versa, the releasing arm will be rocked and will be swung upwardly or downwardly. The pin 91 must be in normal intermediate position when the key is removed and when in this position the releasing arm 49 will fit in the slot 46 as shown in Fig. 2 when the device is unlocked. The slot 46 is shaped to permit the releasing arm to fit therein in reverse position when the latch is locked.

Within the lock body 88 I arrange a dial member 100 which has a finger engaging head portion thereon. The dial member includes a tubular body 101 which rotates in a bore 102 in the lock body 88. The lock body is open at its inner end to receive a closure 103. The closure includes an outer flange 104 which is rotatable within the lock body 88 and an inner flange 105 within which the inner end of the tubular dial body 101 may rotate.

The dial body 101 includes an integral tumbler 106 and supports a pair of other tumblers 107 and 108. The tumblers are provided with the usual pins 109 and the construction is such that by rotating the dial 100 the tumblers may be correctly positioned to align peripheral grooves 110 of which there is one in each tumbler.

The peripheral grooves, when the dials are correctly positioned, are disposed opposite an arm

111, pivoted at 112 to the closure 103. A spring 113 normally urges the arm inwardly in Fig. 3. The arm normally engages the outer face of the tumblers so that a radial pin 114 on the arm which extends through a slot 115 in the flange 104 remains in a slot 115 in the lock body 88. This pin 114 thus locks the closure 103 to the lock body to prevent rotation of the closure.

When the grooves 110 are aligned the spring 113 will move the arm 111 into these grooves, thus withdrawing the pin 114 from the slot 115. Since the tumbler 106 is integral with the dial 100 and since the arm 111 is moved by the spring 113 into all the grooves 110, it will be seen that all the tumblers are thereby keyed together and when the dial is turned the closure 103 will also be turned. A split ring 116 normally holds the closure in place and allows rotation thereof.

The closure 103 supports a sleeve 120 which has ears 121 passing through slots 122 in the closure.

The sleeve 120 slidably receives a lock barrel 124, which has an end 125 which extends through a hole 126 in the dial head 100. Ribs 127 within 25 the sleeve engage in slots 127' in the barrel 124 to prevent rotation of the barrel 124. The details of the lock form no part of the present invention as such locks are common and in well known use.

The construction is such that when a key 128 30 is inserted in the lock and rotated, suitable pins (not shown) will be aligned, permitting the key 128 to turn relative to the lock barrel 124 through 90 degrees in either direction from a normal position. The turning of the key rotates 35 the head member 89 previously mentioned to move the carriage members 36 to locked or unlocked position.

Shoulders 130 and 131 on the barrel 124 and sleeve 120 limit outer movement of the lock barrel. A spring 132 normally urges the lock barrel outwardly.

When the tumblers have been correctly positioned and the arm 111 has been moved into the grooves 110, rotation of the dial member 100 will 45 rotate the dial, tumblers, arm 111 and closure 103, thus rotating the crank 90 to unlock or lock the door. After the unlocking or locking is performed the dial 100 may be slightly rotated in the same direction until the crank pin 91 is arrested by moving the locking bar 81 to its limit of movement. After this is done an increase of pressure on the dial 100 will, due to the cam shape 133 of the grooves 10 and the corresponding cam shape of the arm 111, cause the arm to be cammed out of the grooves so that the pin 114 will enter into the slot 115 and will free the dial tumblers to jumble the latter.

The force required to turn the dial to unlock the latches is not sufficient to cam the arm 111 from the grooves 110. A deliberate movement after the bar 81 has moved to unlocked or locked position is required to release the arm 111 and jumble the tumblers.

In Figs. 6, 7 and 8, wherein a modification of the present invention is illustrated, parts like those described above are indicated by similar single primed reference numerals.

In this modification the lock barrel 140 is shown as being remote from the dial and tumblers. The lock barrel 140 includes a projecting cylinder member 141 similar to the before mentioned member 89 which supports a crank member 142 and a pin 143 which is adapted to operate in a slot 92' in the locking bar 81'.

The dial body, indicated generally at 144, in-

eludes a bore which receives a closure 103'. The closure has an outer flange 104' and an inner flange 105'. Within the body 144 I arrange a dial member 100' which has an end which protrudes through an opening 102' in the body 144. The dial member is rotatable within the flange 105'. The dial member 100' carries integral tumbler 106' and supports a pair of other tumblers 107' and 108'. The tumblers include pins 109'. Peripheral grooves 110' in the tumblers, when correctly positioned, are adapted to be aligned with an arm 111' and the construction and operation of the tumblers and arm 111' is similar to that previously described.

The closure 103' supports a cylindrical head member 144' which may be secured to the closure 103' as by a nut 145. The member 144' supports a crank member 146, the outer end of which is pivotally connected to an arm 147. The arm 147 extends upwardly and is pivotally connected to the crank member 142 as at 148. The crank member 142 is similar in construction and function to the crank member 80 previously described.

Thus it may be seen that codification and operation of the dial member 100' and simultaneous operation of a key 150 in the lock barrel 140 will rock the locking bar 81' to actuate the door latch to unlocked position.

Having thus described my invention, I claim:

1. In a door latch which includes a bolt movable to engaged and released positions, means to hold the bolt in engaged position, means to release the bolt, and locking means for the release means, a chambered body, a dial member rotatable on said body and having tumblers thereon, a rotatable closure on said body, each tumbler having a notch in its periphery, an arm movably mounted on said closure and disposed to enter said notches when the tumblers are correctly positioned, clutch means operative to normally prevent rotation of the closure relative to the body, a head member mounted to rotate with the closure, said head member having an actuating member thereon adapted to engage and shift the locking member, and means to move the arm and free the clutch means from the body so that the closure and head member may be rotated when the dial tumblers are correctly positioned.

2. In an automotive vehicle door latch construction, a bolt movable on the door to engaged and released positions, a push button member on the door operable to release the bolt, locking means for the bolt, and coaxial key operated lock means and permutation tumbler operated lock means each operable to free the bolt locking means so that actuation of the push button will release the bolt.

3. In a vehicle door latch which includes a bolt and a locking member for the bolt, a fixed support, a lock body rotatable on the support, means including a pivoted arm to normally hold the lock body against rotation relative to the support, a head member mounted in the lock body, key released means normally preventing relative rotation between the head member and lock body, tumbler controlled means operable to rock the pivoted arm and free the holding means to permit rotation of the head member and lock body as a unit, and a lock actuating member carried by the head member and movable when the head member is rotated and adapted to move the locking member to unlocked position.

4. In a door latch which includes a bolt and a locking member for the bolt, a body having a chamber therein, a dial body rotatable in said

chamber and having rotatable tumblers thereon, a rotatable closure for said chamber, each tumbler having a notch in its periphery, an arm movably mounted on said closure and disposed to enter said notches when the tumblers are correctly positioned, means carried by said arm and operative to normally prevent rotation of the closure relative to the body, a lock barrel mounted against rotation upon said closure, a head member rotatable in said lock barrel, key released means normally preventing rotation of said head member in said lock barrel, said head member having an actuating member thereon and adapted to engage and shift the locking member, and means to move the arm and free the preventing means and permit rotation of the closure and lock barrel as a unit when the dial tumblers are correctly positioned.

5. In a door latch which includes a bolt and a locking member for the bolt, a body, a dial member rotatable on said body and having rotatable tumblers thereon, a closure rotatable on said body, each tumbler having a notch in its periphery, clutch means operative to normally prevent rotation of the closure relative to the body, a lock barrel fixed against rotation on said closure, a head member rotatable on said lock barrel, key released means normally preventing rotation of said head member in said lock barrel, said head member having an actuating member thereon adapted to engage and shift the locking member, and means to free the clutch means from the body and permit rotation of the closure and lock barrel as a unit when the dial tumblers are correctly positioned.

6. In a door latch which includes a bolt and a locking member for the bolt, a body having a chamber therein, a dial body rotatable in said chamber and having tumblers thereon, a rotatable closure for said chamber, each tumbler having a notch in its periphery, clutch means including a part disposed to enter said notches when the tumblers are correctly positioned and operative to normally prevent rotation of the closure relative to the lock body, a sleeve fixed to the closure, a lock barrel fixed against rotation in said sleeve, a head member rotatable in said lock barrel, key released means normally preventing rotation of said head member in said lock barrel, said head member having an actuating member thereon extending through said closure and adapted to engage the locking member, and means to free the clutch means and permit rotation of the closure, sleeve, lock barrel and head member as a unit when the dial tumblers are correctly positioned.

7. In a door latch which includes a bolt and a locking member for the bolt, a lock body having a chamber therein, a dial body rotatable in said chamber, tumblers rotatable on said dial body, means whereby the dial body rotates the tumblers, a rotatable closure for said chamber, each tumbler having a notch in its periphery, an arm movably mounted on said closure and disposed to enter said notches when the tumblers are correctly positioned, a sleeve fixed to the closure and arranged within the dial body, means carried by said arm to normally prevent rotation of the closure relative to the lock body, a lock barrel fixed against rotation in said sleeve, a head member rotatable in said lock barrel, key released means normally preventing rotation of said head member in said lock barrel, said head member having an actuating member thereon extending through said closure and adapted to

engage and shift the locking member, and means to move the arm and free the preventing means from the lock body and permit rotation of the closure, sleeve, lock barrel and head member as a unit when the dial tumblers are correctly positioned.

8. In a door latch which includes a bolt and a locking member for the bolt, a lock body having a chamber therein, a cylindrical dial body rotatable in said chamber, said dial body including an operating head, tumblers rotatable on said dial body, means whereby the dial body rotates the tumblers, a rotatable closure for said chamber, each tumbler having a notch in its periphery, an arm movably mounted on said closure and disposed to enter said notches when the tumblers are correctly positioned, a sleeve fixed to the closure and arranged within the dial body, means carried by said arm and engaging the lock body to prevent rotation of the closure relative to the lock body, a lock barrel fixed against rotation in said sleeve, a head member rotatable in said lock barrel, means normally preventing rotation of said head member in said lock barrel, key released means normally preventing rotation of said head member in the lock barrel while the barrel remains stationary, said head member having an actuating member thereon extending through said closure and adapted to engage and shift the locking member, and means to move the arm and free the preventing means from the lock body and permit rotation of the closure and lock barrel as a unit when the dial tumblers are correctly positioned.

9. In a door latch which includes a bolt and a locking member for the bolt, a lock body having a chamber therein and having a bore communicating with the chamber, a cylindrical dial body rotatable in said bore, a dial head carried by said dial body, tumblers rotatable on said dial body, means whereby the dial body rotates the tumblers, a rotatable closure for said chamber, each tumbler having a notch in its periphery, an arm pivotally mounted on said closure and disposed to enter said notches when the tumblers are correctly positioned, said dial head projecting beyond the bore for engagement with the fingers of an operator to permit rotation of said dial body, a sleeve fixed to the closure and arranged within said dial body, means carried by the arm to normally prevent rotation of the closure relative to the lock body, a lock barrel fixed within said sleeve against rotation, said dial head having a bore therein, said lock barrel including an end portion extending through said dial head bore, a head member rotatable in said lock barrel, key released means normally preventing rotation of said head member in the lock barrel, said head member having an actuating member thereon extending through said closure and adapted to engage and shift the locking member, and means to move the arm into the notches and free the preventing means and permit rotation of the closure, sleeve, lock barrel and actuating member as a unit when the dial tumblers are correctly positioned.

10. In a door latch which includes a bolt and a locking member for the bolt, a lock body having a chamber therein and having a bore communicating with the chamber, a cylindrical dial body rotatable in said bore, a dial head carried by said dial body, tumblers rotatable on said dial body, means whereby the dial body rotates the tumblers, a rotatable closure for said chamber, each tumbler having a notch in its periphery, an

arm movably mounted on said closure and disposed to enter said notches when the tumblers are correctly positioned, said dial body projecting beyond the bore for engagement with the fingers of an operator to permit rotation of said dial body, a sleeve fixed to the closure and arranged within the dial body, means carried by the arm and engaging the lock body to prevent rotation of the closure relative to the lock body, a lock barrel fixed against rotation in said sleeve, said dial head having a bore therein, said lock barrel including an end portion extending through said dial head bore, a head member rotatable in said lock barrel, key released means normally preventing rotation of said lock barrel head member in the lock barrel, said lock barrel head member having an actuating member thereon extending through said closure and adapted to engage the locking member, and means to move the arm and free the preventing means and permit rotation of the closure, sleeve, lock barrel and actuating member as a unit when the dial tumblers are correctly positioned.

11. In a door latch which includes a bolt and a locking member for the bolt, a lock body having a chamber therein and having a bore communicating with the chamber, a cylindrical dial body rotatable in said bore, a dial head carried by said dial body, tumblers rotatable on said dial body, means whereby the dial body rotates the tumblers, a rotatable closure for said chamber, each tumbler having a notch in its periphery, an arm pivotally mounted on said closure and disposed to enter said notches when the tumblers are correctly positioned, means normally urging the arm towards the tumblers, said dial head projecting beyond the bore for engagement with the fingers of an operator to permit rotation of said dial body, a sleeve fixed to the closure and arranged within said dial body, preventing means carried by said arm to normally prevent rotation of the closure relative to the lock body, a lock barrel slidably within said sleeve, said dial head having a bore therein, said lock barrel including an end portion extending through said dial bore, a head member rotatable in said lock barrel, said head member having an actuating member thereon extending through said closure and adapted to engage the locking member, and means to move the arm and free the preventing means and permit rotation of the closure, sleeve, lock barrel and actuating member as a unit when the dial tumblers are correctly positioned.

12. In a vehicle door latching system, a plurality of doors, a latch for each door, each latch including a bolt movable to engaged and released positions, means to hold the bolt in engaged position, an outside actuator for the bolt, a shiftable carriage member, a release member movably engaging the carriage member, the release member being operable by the outside actuator to shift the bolt holding means to a position to release the bolt, the carriage member being movable to either of two positions, the release member being movable with the carriage member from a locked to unlocked position and vice versa to render the outside actuator operative or inoperative to move the release member to free the bolt, means connecting the several latches for coincidental movement of the carriage members and the release members to unlocked or locked position, a key actuated lock means operable to move the several carriage members and the release members from locked to unlocked positions,

11

and keyless, combination, dial controlled lock means operable to move the several carriage members and the release members from locked to unlocked positions.

13. In a vehicle latching system, a plurality of doors, a latch for each door, each latch including a bolt movable to engaged and released positions, means to hold the bolt in engaged position, an outside actuator for the bolt, a shiftable carriage member, a release member movably engaging the carriage member, the release member being operable by the outside actuator to shift the bolt holding means to a position to release the bolt, the carriage member being shiftable to either of two positions, the release member being movable with the carriage member from a locked to an unlocked position and vice versa to render the associated outside actuator operative or inoperative to move the release member to free the bolt, means connecting the several door latches for coincidental movement of the carriage members and the release members to locked or unlocked position, and a keyless, combination, dial controlled lock means operable to move the carriage members and release members on the several doors from locked to unlocked positions, restoring means operable when the carriage members and the release members of the several latches are in locked position and a door is closed to shift the carriage members and the release members to the unlocked position, and manually operated means effective when the carriage members and the release members are in locked position and a door is closed to render the restoring means ineffective to restore the carriage members and the release members to unlocked position.

14. In a vehicle door latching system, a plurality of doors, a latch for each door, each latch including a bolt movable to engaged and released positions, means to hold the bolt in engaged position, an outside actuator for the bolt, a shiftable carriage member, a release member movably engaging the carriage member, the release member being operable by the outside actuator to shift the bolt holding means to a position to release the bolt, the carriage member being shiftable to either of two positions, the release member being movable with the carriage member from a locked to an unlocked position and vice versa to render the associated outside actuator operative or inoperative to move the release member to free the bolt, means connecting the several door latches for coincidental movement of the carriage members and release members to locked or unlocked position, a key operated lock means operable to move the carriage members and release members in the several latches from locked to unlocked position, and a keyless, combination, dial controlled lock means operable to move the carriage members and release members on the several doors from locked to unlocked positions, restoring means operable when the carriage members and the release members of the several latches are in locked position and a door is closed to shift the carriage members and the release members to the unlocked position, and manually operated means effective when the carriage members and the release members are in locked position and a door is closed to render the restoring means in-

12

effective to restore the carriage members and the release members to unlocked position.

15. A vehicle door latching system as defined in claim 12, wherein the key actuated lock means and the keyless, dial controlled lock means are coaxially arranged.

16. A vehicle door latching system as defined in claim 12, wherein the key actuated lock means and the keyless, dial controlled lock means are spaced apart.

17. In a vehicle door latching system, a plurality of doors, a latch for each door, each latch including a bolt movable to engaged and released positions, means to hold the bolt in engaged position, an outside actuator for the bolt, a release member operable by the outside actuator to shift the bolt holding means to a position to release the bolt, means to mount the release member for movement from a locked to unlocked position and vice versa to render the outside actuator operative or inoperative to move the release member to free the bolt, means connecting the several latches for coincidental movement of the release members to unlocked or locked position, and keyless, combination, dial controlled lock means operable to move the several release members from locked to unlocked positions.

18. In a latch for a vehicle door, said latch including a bolt movable to engaged and released positions, means to hold the bolt in engaged position, an outside actuator for the bolt, a shiftable carriage member, a release member movably engaging the carriage member, the release member being operable by the outside actuator to shift the bolt holding means to a position to release the bolt, the carriage member being shiftable to either of two positions, the release member being movable with the carriage member from a locked to an unlocked position and vice versa to render the associated outside actuator operative or inoperative to move the release member to free the bolt, and a keyless, combination, dial controlled lock means operable to move the carriage member and release member from locked to unlocked positions, restoring means operable when the carriage member and the release member are in locked position and the door is closed to shift the carriage member and the release member to the unlocked position, and manually operated means effective when the carriage member and the release member are in locked position and the door is closed to render the restoring means ineffective to restore the carriage member and the release member to unlocked position.
